IMPROVEMENTS IN AUTOMATIC GUNS HAVING
A DETACHABLE BARREL

Bernard Maillard, Geneva, Switzerland, assignor to
Brevets Aero-Mecaniques S. A., Geneva, Switzerland,
a Swiss society

Application July 22, 1954, Serial No. 445,099

Claims priority, application Luxemburg July 27, 1953

4 Claims. (Cl. 89—193)

The present invention relates to automatic guns having a detachably secured barrel and including in the breech case a mechanism controlled by gases tapped from said barrel.

The chief object of my invention is to provide a gun of this type which is better adapted to meet the requirements of practice, in particular concerning the transmission of the gases tapped from the barrel to the mechanism provided in the breech case.

There are known guns of this type in which the gases are conveyed from the barrel to the mechanism through conduits carried by the barrel and opening into a surface of said barrel which fits, when the barrel is fixed to the breech case, against a corresponding surface from which start corresponding conduits leading to said mechanism. The drawback of this arrangement is that the two above-mentioned cooperating surfaces get jammed against each other due to the unavoidable presence of impurities in the powder gases tapped from the gun barrel.

According to my invention, the gun barrel carries at least one cylinder preferably parallel to the barrel axis and to which the gases are fed from the bore of said barrel, this cylinder opening opposite one end wall of a cylindrical housing carried by the breech case, which end wall is provided with a hole for feeding tapped powder gases to the mechanism to be operated by said gases, a piston provided with a small longitudinal passage extending therethrough being slidable in said cylinder, so that when a shot is fired, the powder gases apply said piston in a gastight manner against said housing end wall and a portion of said gases pass through said longitudinal passage into said housing to operate the above-mentioned mechanism.

A preferred embodiment of my invention will be hereinafter described with reference to the accompanying drawings given merely by way of example and in which:

Fig. 1 is a sectional view on the line I—I of Fig. 3 of a gun made according to my invention.

Fig. 2 is a sectional view on the line II—II of Fig. 3.

Fig. 3 is a cross sectional view on the line III—III of Fig. 2.

My invention will be described as applied to an automatic gun (for instance of a caliber ranging from 20 to 50 mm.) including, to keep its breech-block temporarily in locked position, a movable system controlled, every time a shot is fired, by powder gases tapped from the barrel of the gun.

In the construction illustrated by the drawings, the gun includes a barrel 1 fixed at the rear thereof in a detachable manner to a breech case 2 in which is slidable a breech-block 3 adapted to reciprocate in a direction parallel to the axis of the barrel.

Breech-block 3 is provided with a locking member 4 adapted to bear, once said breech-block has reached its front position, against an abutment piece 5 rigid with breech case 2.

In order to hold locking member 4 in position, there are provided two sliding side bars 6 disposed on either

2

side of breech-block 3 and arranged to bring member 4 into active position and then to hold it in said position during the complementary forward movement performed by said sliding members 6 after the breech-block 3 has reached its front end position.

The whole of breech-block 3 and sliding bars 6 is subjected to the action of a recuperator spring 7 bearing against a cross piece 8 extending between said sliding bars and passing through breech-block 3 provided for this purpose with an elongated slot 9, said piece 8 acting as support for the firing pin 10 of the gun.

Sliding bars 6 are subjected to the action of two springs 29. It is under the combined actions of springs 7 and 29 that the sliding bars perform their supplementary forward displacement during which the member 4 is held in active position and the shot is fired by the firing pin.

Barrel 1 is detachably fixed to breech case 2 by means of screw-threads 11 formed in the rear portion 12 of the barrel engaged in a cylindrical sleeve 13 provided at the front of the breech case.

Barrel 1 is provided with a tap hole 14 opening under a jacket 15 which surrounds the barrel ahead of the portion 12 thereof, this jacket having its rear edge at 16.

I provide in the rear portion of jacket 15, two cylindrical bores 17 having their axes parallel to the barrel axis and opening rearwardly in edge 16, these bores having for instance a diameter averaging 8 mm. for a barrel of a caliber of 20 mm., and being of a length of about 30 mm.

In order to convey the powder gases from tap hole 14 to bores 17, the outer wall of the tube is provided with at least one groove extending rearwardly as far as the transverse plane of the front ends of bores 17 and jacket 15 is provided with passages connecting the rear end of said groove with the front ends of cylindrical bores 17.

For this purpose, the inner surface of jacket 15 may be milled at 18 so as to provide a connection between the inner surface of said jacket and the inside of bores 17.

Advantageously, as shown by the drawing, there is a single groove 19 extending along a generatrix of the outer surface of the barrel and starting from tap hole 14 in the rearward direction to the vicinity of the front end of zone 12. From a point of this groove 19 ahead of the rear end thereof start two other grooves 20 directed in such manner that they lead to points connected through passages 18 with the front ends of bores 17. Thus the portion of groove 19 located rearward of the point from which branch grooves 20 constitutes a kind of dead end in which accumulate the impurities contained in the powder gases, whereby said gases are purified before being led to bores 17.

In each of said cylindrical bores 17, I provide a small piston 21 sliding with a snug fit therein and provided with packing grooves. This piston 21 is provided with an axial passage 22 of a cross section such that the desired amount of gas can flow therethrough.

Advantageously, cylinders 17 are disposed so that their respective axes are located symmetrically with respect to the vertical plane of symmetry of the gun and are in line with the unlocking push-pieces which will now be referred to.

The front portion of breech case 2 is provided with two bores or cylindrical housings 23 disposed in such manner that when the barrel and the breech case are assembled together, these cylindrical housings 23, which open toward the front, are respectively coaxial with the cylinders 17 of jacket 15.

Each of these cylinders 23 is closed at the front end thereof by a plug 24 provided with an axial passage 25.

The rear edges of cylinders 17 are not tightly applied against plugs 24. A piston 26 is slidable in cylindrical housing 23.

A push-piece 27 (already above referred to) is mounted

in the portion of the breech case at the rear of cylindrical housings 23 and this push-piece cooperates through its front end with piston 26 and through its rear end with the front edge of the corresponding sliding bar 6.

This system works in the following manner.

Once a shot has been fired and as soon as the shell has moved in the barrel bore ahead of tap hole 14, powder gases escape through the said hole and pass through grooves 19 and 20 into cylinders 17.

These gases acting upon pistons 21 push said pistons rearwardly, thus strongly applying the rear faces of said pistons against the front faces of plugs 24. If these corresponding surfaces are suitably machined, the high pressure exerted by the gases achieves a good gas-tightness in the zone of contact between said surfaces.

A portion of the gases flows through passages 22 and 25 so as to act upon pistons 26 which are then pushed rearwardly and compel push-pieces 27 to move back, thus driving sliding bars 6 rearwardly.

The breech-block is then released and can therefore reciprocate. When it comes back to its front end position, the sliding bars have a complementary forward stroke as above described and act upon the rear ends of push-pieces 27, which are thrown forwardly. The elements of the breech mechanism are then back in their initial positions and the same cycle again takes place due to the fact that when the sliding bars reach their front end position a new shot is being fired.

Advantageously, means are provided to prevent, during the taking to pieces of the gun, pistons 21 and possibly plugs 24, from dropping from their respective housings. Concerning pistons 21, such means must of course enable the pistons to have the slight axial displacement that is necessary to apply them against plugs 24. Said means may simply consist of a split ring 28 tending to expand outwardly, inserted in a peripheral groove of each piston and elastically applied against the inner wall of cylinder 17.

With the arrangement above described, when the barrel is being detached from the breech case, as pistons 21 are not tightly held against plugs 24, any clogging that might be produced by the impurities between these two elements is avoided and there will be no difficulty in detaching the barrel from the breech case.

Of course, the rate of fire of the gun will depend upon the cross section of passages 22.

It is possible, by changing pistons 21, to vary the rate of fire of the gun and to give it the desired value.

On the contrary, the section of passages 25 will have no influence upon the rate of fire if these passages are of a cross section or area substantially greater than that of passages 22.

In a general manner, while I have, in the above description, disclosed what I deem to be practical and efficient embodiments of my invention, it should be well understood that I do not wish to be limited thereto as there might be changes made in the arrangement, disposition and form of the parts without departing from the principle of the present invention as comprehended within the scope of the accompanying claims.

What I claim is:

1. An automatic gun which comprises, in combination,

a breech case, a barrel detachably fixed to said breech case, said breech case being provided with at least one cylindrical housing for receiving gases tapped from said barrel, one end wall of said housing being provided with a passage extending therethrough, a cylinder carried by said barrel having one end thereof located opposite the outer face of said housing end wall when said barrel is fixed on said breech case, said barrel being provided with at least one tap conduit connecting the bore thereof with the other end of said cylinder, and a piston in said cylinder provided with a longitudinal passage extending therethrough, this passage being in line with said first mentioned passage, the outer end of said piston being shaped to fit against the outer face of said housing end wall when the powder gases escaping from the bore of said barrel through said tap conduit push said piston against said end wall, whereby said two passages are connected together end to end with a gas-tight fit when said gases are to flow therethrough.

2. An automatic gun which comprises, in combination, a breech case, a barrel detachably fixed to said breech case, said breech case being provided with at least one cylindrical housing parallel to said barrel for receiving gases tapped from said barrel, the front end wall of said housing being provided with a passage extending therethrough, a cylinder parallel to said barrel and carried by it having the rear end thereof located opposite the outer face of said housing front end wall when said barrel is fixed on said breech case, said barrel being provided with at least one tap conduit connecting the bore thereof with the front end of said cylinder, and a piston in said cylinder provided with a longitudinal passage extending therethrough, this passage being in line with said first mentioned passage, the outer end of said piston projecting rearwardly from said cylinder and being shaped to fit against the outer face of said housing front end wall when the powder gases escaping from the bore of said barrel through said tap conduit push said piston against said end wall, whereby said two passages are connected together end to end with a gas-tight fit when said gases are to flow therethrough.

3. A gun according to claim 2 in which said tap conduit includes, in said barrel, a longitudinal groove and an oblique groove extending between the front end of said cylinder and a point of said longitudinal groove ahead of the rear end thereof, said gun including a sleeve surrounding the portion of said barrel including said grooves so as to close them.

4. A gun according to claim 2 further including means for preventing said piston from dropping from said cylinder while leaving it free to move to a limited degree therein.
